United States Patent Office

Des. 204,894
Patented May 24, 1966

204,894

CLOCK

Frederick A. Hurley, 10911 NE. 10th Ave.,
Miami, Fla.

Filed Sept. 8, 1964, Ser. No. 81,639

Term of patent 14 years

(Cl. D42—7)

FIG.1

FIG.2

FIGURE 1 is a front oblique view of a clock showing my new design as depicting the hour of 12:55; and

FIGURE 2 is a similar view thereof but depicting the hour of 3:00.

The essential features of my design are shown in full lines.

I claim:

The ornamental design for a clock, as shown and described.
